UNITED STATES PATENT OFFICE

101,503

DESIGN FOR A COMBINED CATHOLIC CRUCIFIX CONTAINER AND SICKROOM SET

John O. Mooney, Rochester, N. Y.

Application February 6, 1935, Serial No. 55,277

Term of patent 7 years

To all whom it may concern:

Be it known that I, John O. Mooney, a citizen of the United States, residing at Rochester, in the county of Monroe and State of New York, have invented a new, original, and ornamental Design for a Combined Catholic Crucifix Container and Sickroom Set, of which the following is a specification.

Reference is had to the accompanying drawings, forming a part of this specification.

In the drawings:

Catholic crucifix container and sickroom set showing the crucifix erected.

The candles and candle holders shown in Figure 1 form an integral part of the assembly, although removable therefrom.

I claim:

The ornamental design for a combined Catholic crucifix container and sickroom set as shown and described.

JOHN O. MOONEY.
